STEP STOOL

Earl F. Hamilton, Columbus, Ind., assignor to Hamilton Cosco, Inc., Columbus, Ind., a corporation of Indiana

Filed Mar. 30, 1959, Ser. No. 55,227

Term of patent 14 years

(Cl. D15—8)

Fig. 1 is a front elevation of a step stool showing my new design;

Fig. 2 is a side elevation thereof; and

Fig. 3 is a plan view thereof.

I claim:

The ornamental design for a step stool, as shown.
